UNITED STATES PATENT OFFICE.

JOHN M. NASH, OF WAUWATOSA, WISCONSIN.

WOOD SANDING OR POLISHING MACHINE.

1,343,981.

Specification of Letters Patent. Patented June 22, 1920.

Application filed November 19, 1917. Serial No. 202,679.

To all whom it may concern:

Be it known that I, JOHN M. NASH, a citizen of the United States, residing at Wauwatosa, county of Milwaukee, and State of Wisconsin, have invented new and useful Improvements in Wood Sanding or Polishing Machines, of which the following is a specification.

My invention relates to improvements in wood sanding or polishing machines, and pertains especially to machines of the general type disclosed in my former Patent #763,315, dated June 21st, 1904, for a machine for reducing wood or other materials.

Prior to the date of my former patent, the common practice was to present the stock, (i. e., the wooden surface to be polished), to a rapidly moving sanding belt, the stock being turned or shifted in a manner to present all sides or surfaces thereof in contact with the belt at some period during the progress of the work. The machine disclosed in my former patent was peculiarly adapted for finishing circular and cylindrical surfaces, it being possible to revolve around articles rapidly in contact with a relatively stationary abrading surface, and in such cases, an advantage is secured owing to the fact that the stationary, or relatively stationary, abrading surface may have its contour varied along a line parallel with the axis of the revolving stock and can thus be made to fit annular grooves and bulging portions in the stock with substantially equal pressure at all points. My invention was peculiarly adapted for finishing surfaces of table legs having circular contours.

But where the surfaces to be finished are not concentric with the axis about which the stock revolves, it is desirable, in order to expedite the work, that the abrading material be actuated across the surfaces to be polished, and that the stock be slowly turned to present various portions of its surface to the abrading material.

In my present invention, I employ a turret somewhat similar to that disclosed in my former patent, but instead of rapidly revolving the stock carried by the turret, my present invention contemplates revolving it slowly and intermittently and presenting it successively to a set of sanding belts during the revolution of the turret.

One object of my invention is to provide means whereby the operation of each sand-

ing belt upon the stock may be commenced and terminated along predetermined lines along the surface of the stock. In this manner, the work of one sanding belt may extend beyond the field of operations of another belt, or if desired, the degree of abrasion may be varied along different longitudinally extending zones in the surface of the stock, or abrasion omitted altogether along certain lines or strips of surface. This feature of my invention is peculiarly adapted for use in connection with spoke sanding machines for the reason that spokes are frequently of a generally oval or elliptical form, with flattened sides converging to a comparatively sharp edge, which, if presented to the abrading surfaces in the ordinary manner, would be rapidly cut away, thereby destroying the design by varying the contour of the spoke and rounding off the angular portions thereof.

By my invention, I am enabled to commence the abrading operation at one side of the apex of an angle or substantially at the apex, and slowly revolve the spoke to carry the apex away from the belt and return it toward the belt on the opposite side, the spoke having, in the mean time, performed nearly a complete revolution without bringing the apex of the angle into edge contact with the sanding belt. Where there is more than one edge or apex, I am enabled to polish an intermediate portion of the spoke in contact with one belt, remove it, turn it and present another intermediate surface to the next belt, etc.

By thus removing material from the spoke at each side of the angles, I am enabled to utilize the sanding belts to increase the sharpness of longitudinally extending edges or angles upon spokes having diamond shaped, egg shaped, or oval designs.

A further object of my invention is to provide efficient means for feeding spokes to a revolving turret and automatically engaging them between chucks carried by the turret.

A further object is to provide improved means for adjusting the tension of the sanding belts, and positioning them in accordance with the requirements of any given class of work.

A still further object is to provide means for increasing the efficiency of the machine by preventing the dust and sand from interfering with its operation, and also by

providing means whereby access may be readily obtained to the working parts of the machine.

In the drawings—

5 Figure 1 is a front elevation of a spoke sanding machine embodying my invention.

Fig. 2 is a side elevation of the same as viewed from the right in Fig. 1 with the right hand turret removed and showing the 10 supporting shaft in cross section.

Fig. 3 is a sectional view drawn on line 3—3 of Fig. 1.

Fig. 4 is a central horizontal sectional view of the parts illustrated in Fig. 3.

15 Fig. 5 is a front elevation on an enlarged scale, showing the feedway and associated parts.

Fig. 6 is a view of the same in side elevation.

20 Fig. 7 is a detail end view of one of the spoke engaging chucks.

Fig. 8 is a side view of the same, partly in longitudinal section.

25 Fig. 9 is a detail view in longitudinal section, showing a fragment of one of the spring actuated, spoke engaging plungers and its associated bearing member.

Fig. 10 is an end view of the same.

30 Figs. 11 and 12 are detail views illustrating means for utilizing the belt tighteners to control the action of the sanding belt.

Fig. 13 is a sectional view on line 13—13 of Fig. 3.

35 Fig. 14 is a sectional view on line 14—14 of Fig. 6.

Fig. 15 is a conventional illustration of the progressive movement of a spoke along the working portions of the belt.

40 Fig. 16 is a detail view in side elevation showing the head stock and spoke receiving hammock.

Like parts are identified by the same reference characters throughout the several 45 views.

The turret and spoke carrying spindles.

A main shaft 1, mounted in suitable frame bearings at 2 and 3, supports the 50 head stock and tail stock members of the turret these members rotating with the shaft. The head stock member comprises a set of wheels 6 and 7 connected at intervals by chuck supporting spindles 8 having 55 spoke engaging chucks 9 at their inner ends and sprocket wheels 10 at their outer ends. These sprocket wheels revolve with the head stock within a relatively stationary rim 12 carried by a disk 13. The chuck 9 is best 60 illustrated in Figs. 7 and 8. It is provided with a concavely tapered socket 17 in its inner face having a set of V shaped ribs or blades 18 extending along the conically tapered surfaces in planes radiating from the 65 axis of the supporting shaft 8. The end of

the spoke received by this chuck is securely held against independent rotation by these blades 18 which bite into the wood of which the spoke is formed under pressure exerted by the spring actuated tail stock spindles 70 as hereinafter explained.

Rotary movement is imparted to the chucks 9 from a set of relatively stationary gear teeth 20. These teeth are preferably in the form of projecting pins or studs carried by segmental flanges 21 connected with the stationary disk 13 underneath the rim 12 of said disk. The teeth of the pinions 10 extend between these pins or studs 20, whereby, when the turret is revolved, the pinions 80 having teeth in mesh with the teeth or pins 20 will be slowly rotated, this rotary movement, of course, being transmitted to the chuck 9 and to the spokes engaged by said chucks. The rotary motion will continue 85 from one end of each segmental set or row of pins 20 to the other end thereof, the degree of rotation being thus determined by the number of such pins. The rotation of any given chuck and its engaged spoke ceases when the pinion passes out of engagement with the pins on one segmental flange 21, this rotation being resumed when the pinion is brought into mesh with the pins or teeth 20 of the next segmental 95 flange 21.

To prevent accidental rotation of a chuck when its associated pinion moves out of mesh with the pins on one of the segmental flanges 21, the hubs 23 of the pinions 10 are 100 squared and adapted to travel along the arcuate surface of a flange 24 carried by a bracket 25 secured to the disk 13 as best shown in Fig. 4. One flat surface of the squared end of pinion hub 23 will travel 105 in substantial contact with the arcuate flange 24 of one of the brackets 25 in each space between successive sets of actuating pins or teeth 20, and these flat surfaces of the hub 23 are so positioned with reference to 110 the teeth of the pinion, that the pinion will be held without movement after passing out of mesh with one set of pins and its teeth presented to the pins of the next set in proper position to enter the spaces between 115 them to effect exactly the degree of spoke rotation required.

By mounting the pins or teeth 20 upon segmental members 21, which are detachably connected by bolts 26 with the disk 13, 120 I am enabled to remove these segmental members and substitute other similar members having a different number of pins in accordance with the requirements for spokes of different types. Brackets 25, having 125 arcuate bearing flanges 24 of differing lengths, may also be provided, whereby the length of the bearing flanges 23 may be varied in inverse proportion of the length of the toothed segments. 130

The tail stock wheels or holders 27 and 28, spring actuated dead or non-rotatable spindles 29, and the spindle actuating rollers 30 connected with the spindle by means of ears 5 or screws 31 extending through slots 32 in the bearing sleeves 33 carried by the wheel or holder 27, are similar in structure and arrangement to the corresponding parts as disclosed in my former patent, except that I 10 have found that the dead spindles, such as are shown in my former patent, tend to become clogged in the bearings 33, owing to quantities of wood fiber from the spokes and sand from the belts entering these bearings 15 through the slots 32, and I have discovered that, by providing longitudinal grooves 35 in the portions of the spindles which are received in these bearings 33, the dust and grit will be received in the grooves and pushed 20 out longitudinally, thereby preventing any tendency of the spindle to become bound or fixed in position in the bearing by the products of abrasion.

This is an exceedingly important feature 25 of my present invention, since it was necessary, heretofore, to frequently stop the machine for the purpose of cleaning these bearings whenever the spindles became clogged to such an extent that they would not respond 30 to the pressure of the springs 36. It will be understood that the spindles 29 are retracted when the rollers 30 are brought into contact with the inclined face 39 of the bracket 40, this movement permitting a discharge 35 of the spoke from its engagement between chuck 9 and the point bearing end of spindle 29, and also permitting a subsequent delivery of another spoke between the chuck and retracted spindle 29 before roller 40 passes out of engagement with the bracket 40 and allows spring 36 to move spindle 29 into spoke gripping position.

Spoke feeding devices.

I have also provided means for feeding 45 spokes to the machine. The arm 44 of the tail stock slide 45 carries a slide bracket 46 having slots 47 adapted to permit the bracket to be adjusted transversely of the machine and secured in various positions by clamping bolts 49 and 50. Vertically movable slides 52 are socketed in upwardly projecting portions 53 of slide 46 and the slides 52 are provided with grooves 54 in which 55 clamping screws 55 are adapted to engage, thereby permitting a vertical adjustment of slides 52. These vertically movable slides 52 support a set of inclined bars 59 and 60, to the end of which, brackets 61 are attached in 60 a position to serve as connecting members, whereby the bars 59 and 60 may be secured to the upper ends of the slides 52 by a set of clamping bolts 62 and 63. The connecting members or brackets are provided with slots 64 through which the bolts 63 pass, thereby 65 permitting a variation of the angle of inclination of the bars 59 and 60. These bars 59 and 60 constitute supporting parts of an inclined feedway down which the spokes S are successively fed into position to be received 70 between successive sets of live spindles and retracted dead spindles, each dead spindle being, of course, released from retracted position upon coming into alinement with the presented spoke.

The spokes in the feedway are longitudinally positioned by end plates 70 and 71. The plate 70 is adjustably connected with the inclined bar 59 by a transversely disposed slide bar 73 adapted to be secured in various 80 positions of adjustment by clamping set screw 74. The plate 71 is provided with supporting arms 75 which may be riveted or otherwise directly secured to the inclined bar 60.

With this construction, the feedway may be adapted for spokes of differing length, the plate 70 being moved inwardly toward the plate 71 when short spokes are to be fed and moved outwardly when longer spokes 90 are to be delivered to the machine. Similarly the tail stock slide 45 may be adjusted transversely along the bed 77, (Fig. 1), by means of the hand wheel 78, shaft 79, bevel gears 80, and adjusting screw shaft 81, the latter having threaded engagement with a depending arm 82 carried by tail stock slide 45. After the feedway plate 70 has been adjusted in accordance with the length of the spokes to be fed to the machine, slide 46 may be adjusted 100 to so position the feedway that the lower spoke thereon may be properly presented between the chuck 9 and the dead spindle 29 when the spindles arrive in a position to receive such spoke, the dead spindle being also 105 simultaneously released by the bracket 40. The dead spindle is thereupon driven by its spring into engagement with the tenon of the spoke, the foot of the spoke being thus forced into the chuck 9 carried by the opposing live spindle.

The lower spoke on the feedway is supported by a cross bar 85. In Fig. 6, these spokes are shown by dotted lines mounted on the slideway with converging sides projecting upwardly forming a comparatively sharp angle at 87. By uniformly placing the spokes upon the slideway in this position, they will be held in such position by the foot portions, the latter being rectangular in cross section. These foot portions, in moving down the slideway, pass underneath a guide shoe 88 which overhangs the bar 60 and is supported from the bar by an arm 91 secured to the under surface of the bar and with which the shoe is adjustably connected by a set screw 92 extending through a slot 93 in a flange 94 depending from the shoe 88. The slot 93 is curved and the upper margin of the shoe 130

is also curved upwardly, the intermediate portions of the shoe between its upper and lower margins being spaced from the bar 60 in substantial correspondence with the 5 thickness of the foot portion of the spoke. Therefore the spokes placed in this feedway will be guided and positioned by the shoe in passing downwardly to the cross bar stop 85. The shoe also prevents the spokes 10 from being dislodged or disengaged by the resulting shock when the spring actuated dead spindle engages the tenon of the presented spoke and drives the spoke laterally into engagement with the chuck 9. This 15 shock and the movement of the remaining spokes resulting from the shifting of the lower spoke into engagement with the chuck 9 is most effective for a disarrangement of the spokes at about the position occupied by 20 the shoe 88 as shown in Fig. 6. The third, fourth, and fifth spokes above the one engaged by the spindle are the only ones which are likely to be dislodged or disarranged by the shocks transmitted from the bottom 25 spoke of the series. Therefore by locating the guide shoe at this point, I am enabled to counteract such tendency and to also effectively control the downward feed movements of the spokes in the slideway when 30 the lower spoke is lifted and removed by the turret.

Spoke removing mechanism.

A set of inclined knock out bars 100 are 35 secured to the upwardly projecting portion 53 of slide 46 at 101. Arms 102 on these bars are adapted to support them at the proper inclination. The lower ends of these bars 100 extend across the path of the 40 spokes carried by the revolving turret, but they cross the path of the spokes in a plane above the level at which the upwardly moving dead spindles 29 are retracted by having their rollers 30 brought into contact 45 with the inclined face 39 of bracket 40. The weight of the spokes will normally cause it to drop by gravity into a chute 105 as soon as the dead spindle has been retracted from gripping position, but if the 50 chuck plates 18 tend to retain the spoke, the latter will be dislodged therefrom on coming in contact with these inclined knock out plates 100.

The spokes discharged from the turret 55 are received by an inclined trough 105 down which they slide to a belt conveyer 106 which carries them to any suitable point of delivery. In the drawings, the discharge end of this conveyer is shown in an elevated 60 position, whereby the spokes may be delivered directly to a car or into any suitable receiver.

The sanding belts.

65 After being engaged by the spindles and

removed from the feedway, each spoke is carried upwardly by the revolution of the turret into contact with the sanding belt 110. This belt is a narrow belt and is used for sanding or polishing the filet of the 70 spoke. This belt 110 runs over end pulleys 111 and 112 respectively and also over an intermediate positioning pulley 113, whereby the working portion of the belt between this pulley 113 and pulley 111 is held in 75 proper position for operation upon the filet of the spoke. A tension pulley 114 is supported by lever 115 having a counterweight 116, whereby the pulley 114 is pushed upwardly against the belt 110 on the return 80 side. An adjusting screw 117 is also employed to regulate the tension of the belt, pulley 111 being supported from the main belt supporting frame 120 by longitudinally adjustable arms 121. 85

The spoke is rotated while in contact with this belt by the upper set or segmental row or teeth 20. The sanding belt is driven from any suitable source of power, such as an overhead shaft, by means of a pulley 90 122 running over pulley 123.

After the spoke has been carried out of contact with the filet sanding belt 110, it is presented to a sanding belt 130 traveling over pulley 131 and idle pulleys 132 and 133. 95 Pulley 131 is driven by belt 135 and pulley 136. The working portion of this belt is the portion traveling between pulleys 132 and 133, the spoke being presented by the turret to this belt in an exact predetermined 100 position, and then partially or wholly rotated while in contact with the belt in accordance with the requirements of the sanding operation to be performed, the degree of rotation depending, of course, upon the 105 number of pins 20 in the segmental row at the rear side of the machine. This belt is preferably provided with a rough abrading surface, whereby the surface of the spoke may be roughly contoured in accordance 110 with the required design. 135' is a tension pulley or roller, the pressure of which is determined by the counterweight 136'.

Pulleys 132 and 133 are supported by arms 140 and 141 respectively, each of these 115 arms being pivoted to the frame at 143 and adjustably secured thereto by clamping screws 144 operating through curved slots 145 in the supporting frame, whereby the pulleys 132 and 133 may be adjusted forwardly or backwardly with reference to the turret, thereby varying the length of time that the spoke will be in contact with the belt. When the number of pins 20 is varied, these pulleys will also preferably be adjusted 120 so that the spoke will only be in contact with the belt while it is being rotated.

The continued rotation of the turret carries each spoke from the field of operation of the belt 130 and presents it to a finish- 130

ing belt 150 which runs over the end pulleys 152 and 153 and an intermediate pulley 154, the operating portion of the belt being that between pulley 153 and pulley 154. This belt being employed for finishing purposes, will have a comparatively smooth surface, *i. e.*, a surface coated with fine sand. Its operation will be similar to that of belt 130, and its tension is regulated by a tension 5 roller 156 supported by lever 157 having a counterweight 158.

In Fig. 11, I have illustrated means whereby the tendency of a belt to shift transversely upon its supporting and actuating pulleys may be corrected. The contour 15 of the spoke is frequently such as to cause the belt to shift upon or over the pulleys. For example, a tapered spoke will tend to crowd the belt toward the smaller end of 20 the spoke. This tendency can be counteracted by employing a belt tighter pulley of the type shown in Fig. 11 wherein a pulley 160 is mounted upon an axle 161. The portion of which within the pulley is 25 inclined with reference to a portion 163 which is socketed in the supporting lever 164. This axle or shaft may be adjustably rotated in its bearing in the lever arm and locked in various positions of adjustment by 30 a set screw 165. A handle 167 facilitates this rotative adjustment.

By means of the rotative adjustment of the pulley supporting axle shaft 161, the pulley may be tilted axially to vary the 35 pressure of its respective ends upon the belt. The pressure may thus be increased on that side of the belt toward which the belt tends to shift, thereby counteracting such tendency.

40 The removal head plate 13.

Aside from the sanding belts, the parts of the machine requiring most frequent alteration, either for repair or adjustment, 45 are contained within the rim 12 of the head plate or disk 13. Therefore to make access to these parts convenient, I make the head stock frame 170 longitudinally adjustable upon the bed 77, and actuate it by means 50 of a hand wheel 171 through bevel gears 172, and adjusting screw shaft 173. By moving the head stock to the right in Fig. 1, the spindles and their operating pinions 10 may be withdrawn from underneath the rim 12. 55 The latter is supported from the bed by standards 175 and clamping bolts 176 which pass through slots 177 and secure this head plate or disk 13 in position. By removing these bolts 176 after the pinions have been 60 withdrawn from within the rim 12, this disk and the rim may be lifted and removed, whereby access to the head stock from both sides will be permitted. The disk is provided with a notch or recess 180 extending 65 from its center downwardly through the

rim on the under side, whereby this head disk 13 may be removed vertically without disturbing the supporting shaft 1. The removal of the head disk permits access to the pinions 10 and pins 20, whereby the number 70 of pins in any given set may be changed at pleasure.

It will be observed that the working portions of the sanding belts normally tend to extend along a line tangent to a circle which is slightly less in diameter than that along which the spokes travel. The belts yield under the pressure of the spokes thereon and this pressure increases until the spoke reaches the central working portion of the 80 belt, after which, it diminishes.

By properly arranging the pinion actuating projections 20, I am able to complete the revolution of the spoke either by presenting its edge or angle to the sanding belt 85 at a point where the belt will operate under light pressure, or in cases where a sharp angle or edge is to be formed upon the spoke, it may be revolved in contact with the sanding belt in such a manner that, as this edge 90 or angle relatively approaches the belt, contact of the spoke with the belt will cease entirely and the axial rotation of the spoke may then be completed to a point where the other side of the angle will be presented to 95 the succeeding belt. In this manner, it is possible to avoid any abrading operation at the apex of the angle while providing for abrasion on each side thereof with light pressure in close proximity to such apex. 100

In the construction illustrated, there are fourteen projections or pins 20 in the segmental member 21 associated with the upper or fillet sanding belt. The same number of projections are associated with the rough 105 sanding belt 130, whereas the smooth sanding belt or buffing belt 150 may, with advantage, be operated over the entire surface of the spoke, including the edge, and I have therefore provided seventeen pins or projections 20, this being the number required to completely rotate the spoke. 110

It will, of course, be understood that, where the spoke is not completely rotated by the projections 20, such rotation will be made 115 complete when the corner of the squared end of pinion hub 23 strikes the end of the adjacent arcuate flange 24, it being necessary that the flat surface of the hub be substantially parallel with the opposing surface of 120 this flange in order to pass over it.

The head piece or disk 13 may be rotatively adjusted by loosening the clamping bolts 176, these bolts passing through the slots 177, in the head piece, as shown in Fig. 125 3. In this manner, the rotation of the spokes carried by the turret may be exactly timed with reference to the intervals during which they are in contact with the sanding belt. 130

It sometimes happens that a spoke imperfectly engaged by the spindle, (as may be the case where the spoke is not of standard length), will be dislodged from between the 5 spindles under the pressure of the sanding belt. This will usually occur either while the spoke is being moved along the filet sanding belt, or during the initial portion of its movement along the rough sanding belt. 10 In either case, the spoke will be thrown inwardly toward the shaft by the reaction of the spring actuated dead spindle. These spokes may therefore be caught in a hammock 190 suspended between the head stock 15 and tail stock underneath the shaft 1 by a forked arm 191 projecting upwardly from the bed. This prevents the spokes from dropping to the lower belt which, if permitted, might result in the destruction of the 20 belt or damage to parts of the turret.

While I have shown and described my invention with reference to a structure in which the spoke is rotated while in contact with the sanding belt and held against rotation at intermediate points, it will be understood that, where spokes having flat surfaces are to be sanded, they may be held against rotation while in contact with the abrading devices or belts and rotated to any 25 desired extent while traveling from one abrading device to another. This result can be attained by merely changing the relative positions of the teeth 20 and the guiding members 24.

35 I claim:

1. In a wood polishing machine, the combination with revoluble sanding belts, of a carrier adapted to convey the stock successively into and out of contact with the belts, 40 means for utilizing the carrier movement to partially rotate the stock about its own axis while in effective contact with the belt, means for completing the rotation of the spoke while out of effective contact with the belt, and means for limiting such rotary movement to a single revolution, whereby the stock may be presented by the carrier to a succeeding belt in substantially the same 45 relative position which it occupied with reference to the first belt when presented thereto.

2. In a wood polishing machine, the combination of a work carrying turret, a sanding belt in operative relation to the work 55 carried by the turret, means connected with the turret for rotatively presenting the work to the belt with pressures which vary in different stages of a single rotation in accordance with the requirements of the various 60 surfaces to be polished, and means for holding the work against axial rotation preparatory to its presentation to the belt, whereby the sanding operation may be commenced along a predetermined line.

65 3. In a wood polishing machine, the com-

bination with a sanding belt, of a revoluble turret provided with annular series of spoke holders adapted to carry spokes into and out of contact with said belt, a relatively stationary member adjacent to one series of 70 spoke holders and provided with segmental rows of projections adapted to serve as pinion actuating teeth, and pinions carried by the spoke holders of the associated series and adapted to travel into and out of mesh 75 with said projections during the rotation of the turret.

4. In a wood polishing machine, the combination with a sanding belt, of a revoluble turret provided with annular series of spoke 80 holders adapted to carry spokes into and out of contact with said belt, a relatively stationary member adjacent to one series of spoke holders and provided with segmental rows of projections adapted to serve as 85 pinion actuating teeth, and pinions carried by the spoke holders of the associated series and adapted to travel into and out of mesh with said projections during the rotation of the turret, said pinions being provided with hubs having flat sides and the relatively stationary member being provided with guiding segments between the segmental rows of projections adapted to prevent rotation of the pinions and spoke 90 holders while traveling from one set of actuating projections to the next.

5. In a wood polishing machine, the combination with a sanding belt, of a revoluble carrier provided with annular series of 100 spoke holders arranged in sets of opposing holders, pinions carried by the spoke holders of one series, a segmental set of relatively stationary pinion actuating members, and means for preventing rotation of the 105 pinions when out of mesh with the actuating members; said carrier being adapted to convey the spokes engaged by said spoke holders along a fixed line of travel into and out of contact with said belt, whereby the 110 area of spoke surface to be polished and also the degree of abrasion may be predetermined.

6. In a wood polishing machine, the combination of a revoluble turret head provided 115 with chuck carrying live spindles, pinions mounted on each spindle, a relatively stationary head member, segmental members mounted on said relatively stationary head and provided with pinion engaging spindle 120 actuating projections.

7. In a wood polishing machine, the combination of a revoluble turret provided with spoke holders flattened at their outer ends and having actuating pinions, a relatively 125 stationary head provided with segmental rows of projections adapted to engage and actuate the pinions when the turret is rotated, and intermediate segmental bearing surfaces adapted to receive the flattened 130

portions of the work holders and prevent the latter from rotating while traveling from one set of segmental projections to the next.

8. In a wood polishing machine, the combination of a revoluble turret provided with spoke holders flattened at their outer ends and having actuating pinions, a relatively stationary head provided with segmental rows of projections adapted to engage and 10 actuate the pinions when the turret is rotated, and intermediate segmental bearing surfaces adapted to receive the flattened portions of the work holders and prevent the latter from rotating while traveling from 15 one set of segmental projections to the next, said projections being removable and adapted to be increased or diminished in number in accordance with the requirements of the work.

20 9. In a wood polishing machine, the combination of a revoluble turret provided with an annular series of work engaging chucks, and a corresponding series of spring actuated, idle spindles, each adapted to engage 25 the work between it and one of said chucks and each having a longitudinally grooved end portion adapted to slide in a turret bearing, said turret being provided with a spindle supporting bearing member.

30 10. In a wood polishing machine, a reciprocating work engaging, idle spindle having a longitudinally grooved gudgeon.

11. In a wood polishing machine, a reciprocating work engaging, idle spindle having a longitudinally grooved gudgeon, in combination with a supporting turret wheel having slotted bearing apertures to receive said gudgeon, and a spindle actuating projection connected with the gudgeon and 40 adapted to slide in the bearing member slot.

12. In a wood polishing machine, a feedway comprising an inclined spoke support, adapted to hold spokes thereon transversely to the line of feed, and with the same side 45 uniformly up, in combination with inclined relatively adjustable plates, constituting guiding walls for the ends of the spokes, and a work stop located along the lower side margin of the spoke support below the lower 50 ends of the end plates, whereby the ends of the lower spoke may be exposed in a position for engagement by a traveling chuck when such spoke is in contact with said stop.

55 13. In a wood polishing machine having a revoluble work carrying turret provided with a series of work engaging chucks, and co-operating, spring actuated, work engaging spindles, the combination with the turret, of an inclined feedway along which the work 60 may be delivered between the spring actuated members and chucks, means for permitting universal adjustment of said feedway, clamping devices for holding the feedway in 65 various desired positions of adjustment,

means for holding the successive pieces of work in parallel positions on the feedway, and a stop at the lower end of the feedway adapted to hold one of the pieces in position for delivery to the turret.

70 14. In a wood polishing machine having a revoluble work carrying turret provided with a series of work engaging chucks, and co-operating, spring, actuated, work engaging spindles, the combination with the turret, 75 of an inclined feedway along which the work may be delivered between the spring actuated members and chucks, means for permitting universal adjustment of said feedway, clamping devices for holding the feedway in 80 various desired positions of adjustment, means for holding the successive pieces of work in parallel positions on the feedway, a stop at the lower end of the feedway adapted to hold one of the pieces in position for delivery to the turret, together with an inclined knock out member loosely suspended beneath the feedway, and means for retracting the 85 spring actuated, work engaging members as the work approaches said knock out member. 90

15. In a wood polishing machine, the combination of a revoluble turret provided with an annular series of spoke engaging chucks each having a conically tapered socket to receive the foot of the spoke, and a set of 95 radial guide ribs projecting from the tapered walls of said socket and adapted to facilitate centering the foot of the spoke in the chuck.

16. In a wood polishing machine, the combination of a turret provided with an annular series of work engaging chucks each having a tapered socket provided with edged guide ribs extending radially along diverging walls of the socket and adapted to direct the work toward the center of the chuck, an 100 opposing, spring actuated, work engaging member carried by the turret, means for retracting said member at one stage of turret rotation, and means for feeding work between the retracted member and the chuck, 105 said retracted member being adapted to automatically engage the work when released from the retractive means by the continued rotation of the turret, whereby the work is driven forcibly into the chuck socket. 110

17. In a wood polishing machine, the combination with a polishing belt, of a revoluble turret provided with annular series of work holders adapted to carry the work into and out of contact with said belt, a belt tightener, and means for varying the pressure of the belt tightener along a line transverse to the polishing belt to counteract shifting tendencies due to the movement of the belt from inclined surfaces of the work.

125 18. In a wood polishing machine, the combination of a work holding turret provided with an axially movable tail stock, a polishing belt in operative relation to work carried by said turret, and an exten- 130

sible feedway slide having one side thereof adjustable in correspondence with the axial adjustment of the tail stock, whereby work of differing length may be accommodated.

19. In a wood polishing machine, the combination of a work holding turret provided with an axially movable tail stock, a polishing belt in operative relation to work carried by said turret, an extensible feedway slide having one side thereof adjustable in correspondence with the axial adjustment of the tail stock, whereby work of differing length may be accommodated, together with means for bodily adjusting the feed slide along the axis of the turret, and additional means for adjusting the same vertically.

20. In a wood polishing machine, the combination of a work holding turret provided with an axially movable tail stock, a polishing belt in operative relation to work carried by said turret, an extensible feedway slide having one side thereof adjustable in correspondence with the axial adjustment of the tail stock, whereby work of differing length may be accommodated, together with means for bodily adjusting the feed slide along the axis of the turret, and additional means for adjusting the same vertically and for varying its inclination.

21. In a wood polishing machine, the combination with a work carrying turret provided with means for automatically and successively engaging pieces of work and presenting them to polishing belts, revoluble polishing belts in operative relation to work carried by the turret, and an inclined feedway slide adapted to receive and support a series of pieces of work and having its lower end extending between the paths traversed by the work engaging portions of the turret and adapted to support the lower piece of work in a position to be engaged and removed by the work engaging members of the turret.

22. In a wood polishing machine, the combination of a revoluble turret provided with annular series of spoke holders, a polishing belt in operative relation to the turret, a relatively stationary actuating member for one series of work holders, motion transmitting devices carried by said work holders in position to be intermittently engaged and actuated by said head in a predetermined cycle of movement, whereby the work presented to the polishing belt by the turret may be intermittently rotated and the polishing operation regulated.

23. In a wood polishing machine, the combination of a revoluble turret provided with head and tail stock members, and an axial supporting shaft, pinions operatively connected with the head stock members, a

relatively stationary head coöperating with the head stock to inclose said pinions and provided with detachable pinion actuating projections, and means for axial adjustment of the head stock to expose said pinions and removable projections, whereby the number of said projections may be varied in accordance with the requirements of the work.

24. In a wood polishing machine, the combination of a revoluble turret provided with head and tail stock members, and an axial supporting shaft, pinions operatively connected with the head stock members, a relatively stationary head coöperating with the head stock to inclose said pinions and provided with detachable pinion actuating projections, and means for axial adjustment of the head stock to expose said pinions and removable projections, whereby the number of said projections may be varied in accordance with the requirements of the work, together with means for axially adjusting the tail stock members to suit the requirements for work of differing length.

25. In a wood polishing machine, the combination of a revoluble turret provided with annular series of coöperating work holders, a revoluble sanding belt having a portion thereof extending across the path of the work carried by the work holders, an inclined slideway adapted to support a series of contacting spokes and provided with a stop adapted to support the lower spoke in position for engagement by said work holders at one side of the turret, work releasing devices operative below said feedway to discharge the polished work, a chute adapted to receive the polished work from the turret, and a conveyer adapted to receive the work from the lower end of the chute.

26. In a wood polishing machine, the combination with a revoluble spoke carrying wheel, provided with rotatable spoke holders, abrading devices grouped about the wheel in the path of spokes carried by the holders, and a positioning member also connected with the spoke holder and adapted for coöperation with a fixed guide to prevent rotation of the spoke holder during the intervals when the spokes are out of contact with the abrading devices.

27. In a wood polishing machine, a rotatable spoke holder, means for intermittently rotating the spoke holder in definite one turn movements, means for abrading spokes carried thereby during a definite portion of their one turn movements, and means for preventing rotation of the spoke holder in the intervening intervals.

28. In a wood polishing machine, the combination with a spoke carrier provided with a series of spoke holders, an abrading device in the path of spokes conveyed by the

carrier, means for utilizing the carrier to rotate the spokes while in contact with the abrading device, and means for positioning the spokes upon the carrier and limiting the 5 rotation thereof to less than a complete turn when in contact with the abrading device.

29. The combination with a spoke carrier, of a set of abrading devices each in the path of the spokes conveyed by said carrier, 10 means for automatically positioning the spokes on the carrier with reference to a predetermined longitudinal line thereon at which abrasion is to commence, means for imparting to the spokes a predetermined rotative movement while they are in contact with the abrading devices, and means for holding the spokes against additional ro- 15

tative movement while passing from one abrading device to another.

30. In a spoke sanding machine, the combination with a spoke carrier, sanding devices, means for intermittently imparting a predetermined degree of rotation to the spokes conveyed by the carrier, and means for controlling said rotative movements to uniformly start rotation from predetermined longitudinal lines on the spokes. 20 25

In testimony whereof I affix my signature in the presence of two witnesses.

JOHN M. NASH.
